ROLLING MILL

Axel Gustav Edvard Leufven, Goteborg, Sweden, assignor to Aktiebolaget Svenska Kullagerfabriken, Goteborg, Sweden, a corporation of Sweden

Application August 7, 1952, Serial No. 303,045

Claims priority, application Sweden February 5, 1945

5 Claims. (Cl. 80—56)

The present invention relates to rolling mills and is a continuation-in-part of my application, Serial Number 644,445, filed January 31, 1946, now abandoned.

A primary object of the present invention is to facilitate the changing of the rolls in rolling mills and thereby to increase the capacity of the mill.

Another object is to render more economical the design of the rolling mill by dispensing with the expensive and bulky stands.

Still another object of the invention is to decrease the give or yield in the mill and thereby to permit rolling to closer tolerances.

A further object of the invention is to provide a mill wherein it is possible to use a smaller roll diameter with a consequent saving in the cost of the rolls. Smaller rolls also afford lower roll pressure and less power requirement.

These and other objects and the various features of the invention are set forth and described in detail in the specification of which the attached drawings constitute a part, wherein:

Fig. 1 is a side elevational view of one embodiment of the present invention;

Fig. 2 is a transverse vertical section of one side of the mill illustrated in Fig. 1;

Fig. 3 is a front elevation of a second and preferred embodiment of the present invention;

Fig. 4 is an end elevation of the embodiment illustrated in Fig. 3;

Fig. 5 is a fragmentary transverse vertical section taken on line 5—5 of Fig. 4;

Fig. 6 is a fragmentary longitudinal vertical section taken on the line 6—6 of Fig. 5;

Fig. 7 is a fragmentary longitudinal horizontal section taken on the line 7—7 of Fig. 3;

Fig. 8 is a fragmentary section taken on the line 8—8 of Fig. 4; and,

Fig. 9 is a fragmentary section taken on the line 9—9 of Fig. 4.

Referring now to the drawings and more particularly to the rolling mill illustrated in Figs. 1 and 2 thereof, the mill is supplied with top and bottom work rolls 1 and 2, the necks 3 and 4 of which are carried in roller bearings 5 and 6, mounted in journal boxes 7 and 8 respectively. Instead of being mounted in the usual stands, each lower box 8 is bolted directly to the bed, and the corresponding upper box 7 is bolted to the box 8 by means of a pair of strong bolts 9 engaging tapped holes 10 in the box 8, but passing freely through holes 11 in the box 7. The boxes are held together by nuts 12, so as to obviate the necessity for stands or the like.

The distance between the rolls is adjusted approximately by spacers 33 and shims 34 surrounding the bolts 9. The nuts are tightened until a considerable preloading is imposed on the bolts 9, the spacers 33 and the journal boxes 7 and 8. The parts of the boxes surrounding the bolts which are subjected to preloading have a considerably greater cross-sectional area than the bolts

2

themselves. By bolting the boxes together with a total force in excess of the roll pressure the yield of the rolls in the mill when rolling is considerably decreased. The rollers therefore maintain their relative positions and it is possible to roll to closer tolerances.

To permit fine adjustments to be made, the bearing 5 at each end of the roll 1 is mounted in a sleeve 13, the inner and outer cylindrical surfaces of which are eccentric to each other. The sleeve 13 can be turned in the boxes 7 and is retained in axial position by a split ring 14, which engages a groove 15 in the sleeve. The sleeve is provided with a projection 16 to which a socketed lever can be applied, and by means of which the sleeve can be turned in the box. The eccentricity of the sleeve is about .5 to 2 mm. and the position of the roll can, therefore, be adjusted about $\pm .35$ to ± 1.5 mm. for a quarter turn of the sleeve 13. This is sufficient to cover the intervals which may be conveniently obtained by the use of shims together with the spacers. By these means it is possible to adjust the distance very accurately between the rolls 1 and 2.

When rolling wire it is necessary that the grooves in the rolls are accurately adjusted opposite each other and it is therefore necessary to make provision for adjusting the rolls axially relative to each other. In the embodiment of the invention illustrated in Figs. 1 and 2, this adjustment is made by shifting the roll 2 relative to the roll 1, for which reason the bearing 6 is slideable relative to the box 8. Between the bearing 6 and the box 8 is a sleeve 17, the inner and outer cylindrical surfaces of which are concentric. The sleeve 17 is threaded at its outer end as shown at 18. These threads engage with threads on a ring 20 fixed to the box 8 by means of screws 19. The bearing is held between a shoulder 25 on the sleeve 17 and a sealing ring 26 is screwed into the sleeve 17. The bearing 6 is consequently held in a fixed position relative to the sleeve.

A ring 21 is provided for turning the sleeve 17. The ring 21 has tongues 22, which engage with grooves 23 in the sleeve 17 and it also has a projection 24 to which can be applied a socketed lever for turning the ring 21 and also the sleeve 17. As the sleeve 17 is turned it is shifted axially due to its threaded engagement with the ring 20 in the manner of a screw in a nut.

The bearing 6 takes part in the axial movement and, since the bearing is mounted on a tapered portion 27 of the roll neck and is held in place by a sleeve 28 which is shrunk onto the said neck, the roll 2 will be shifted in a direction depending upon the direction in which the ring 21 is turned. The amount of this movement can be about 1 mm., but may be more or less depending upon the special conditions in each case.

To change rolls it is only necessary to loosen the journal boxes 7 and 8 from the bed and replace them with a second pair of rolls, the boxes of which have already been provided with spacers 33 of the correct size, after which the more accurate adjustments can be made by means of the sleeves 13 and 17. The main adjustments have therefore already been made in advance and the fine adjustments required after the boxes have been put in place can be carried out very easily and quickly.

Referring now to the preferred embodiment of the invention illustrated in Figs. 3 to 9 inclusive, the rolling mill comprises upper and lower work rolls 35 and 36 respectively. The rolls are mounted in a generally horizontal position in roller bearings 37 and 38 which are mounted in journal boxes 39 and 40 respectively, as clearly illustrated in Fig. 5. The lower journal boxes 40 are mounted directly on the bed 42 of the mill and the upper boxes 39 are mounted in superimposed relation up on the corresponding lower boxes 40. To prevent lateral displacement of the assembled boxes, the boxes and the bed are provided with vertically aligned lugs 43

having registering apertures for the reception of locking pins 44 as clearly illustrated in Fig. 3.

As with the previous embodiment, spacers 41 are provided between the upper and lower boxes 39 and 40, and the spacers and the boxes are held together by suitable means susceptible to preloading. In the present instance, the holding means comprises flat bars 45 which are received in registering vertical slots 46 in the journal boxes 39 and 40 and in the spacers 41. The lower end of each bar 45 is pivotally mounted in the bed 42 of the mill as by pins 47. In this manner the bars 45 which normally are engaged in the slots 46 may be readily rocked out of engagement therewith to the position illustrated in broken lines in Fig. 4. To secure the bars 45 in operative positions and to preload the bars, hydraulic tensioning nuts 49 are provided on the upper extremities of the bars 45. The tensioning nuts seat on the upper surfaces of the boxes 40 and are characterized by means for exerting a high degree of tension on the bars in the tightening operation so as to provide a substantial preload on the assembly. The nuts 49 are made in accordance with my Patent No. 2,571,265, issued October 16, 1951, and will not be described in detail here.

In order to provide finer adjustment of the relative radial positions of the upper and lower rolls than afforded by the spacers, each of the opposite end bearings 37 of the upper roll 35 is mounted in a sleeve assembly 50 which provides both radial and axial adjustment of the roll, so that the lower roll may have its associated bearings 38 fixed in the journal boxes 40. The outer ring of the bearing 37 is axially fixed in the sleeve 51 of assembly 50, illustrated in Fig. 5, and the sleeve is slidably mounted in the box 39 for both rotary and axial adjustments therein. The inner and outer cylindrical surfaces of the sleeve are eccentric to each other (see Fig. 6) so that the vertical position of the upper roll 35 may be adjusted by simple rotation of the sleeve in the journal box. The sleeve extends outwardly beyond face of the journal box 39, and is formed on its exposed cylindrical surface with suitable teeth 52 to constitute a worm wheel for engagement with a worm 53 as more fully described hereinafter. To provide for axial adjustment of the sleeve 51 a radial flange 54 is fixed to the sleeve beyond the teeth 52 as more clearly illustrated in Figs. 5 and 9. The flange 54 is adapted to be clamped between suitable dogs 55, 55 which are adjustable relative to the journal box 39 to determine the axial position of the sleeve 51, and therefore the roll 35, as more fully described herein-after.

Rotary adjustment of the sleeve 51 at each end of the roll is effected by the worm 53 which engages the teeth 52 described above. Each worm is mounted in a suitable casing 57 which is bolted to the outer face of the journal box 39. To actuate the worms 53, rotary hand wheels 58, 58 are provided on shafts 59, 60 disposed longitudinally above the roll 35 one concentrically within the other as illustrated in Fig. 8. Each shaft may be actuated independently of the other and is provided with a bevel gear 61 which engages a similar bevel gear 62 connected by means of a shaft 63 to the worm 53. Thus, by rotating either one of the hand wheels 58, the corresponding worm 53 may be actuated to rotate the sleeve 51 in the box 39. In this manner each end of the roll 35 may be adjusted vertically, independently of the other.

Each of the sleeve assemblies 50 is adjustable axially in its journal box 39 by means of the associated dogs 55. Each set of dogs is adjustably mounted on the journal box 39 by means of a stud 65 which is fixed in the box as indicated at 66. The dogs are slidable longitudinally of the stud and can be locked in place by a pair of nuts 67, 67 as clearly illustrated in Figs. 4 and 9. It should be noted with reference to Fig. 4 that there are two sets of dogs for each sleeve spaced 180° apart. Axial adjustment of the sleeve assemblies as described above ef-

fects a corresponding adjustment of the associated bearings and of the upper roll to which the inner race ring of the bearing is attached.

By the aforescribed means, the sleeves 51 may be turned to adjust the upper roll toward or from the lower roll, and also may be adjusted axially to accurately align the grooves in the two rolls. The sleeves required for the lower roll in the previously described embodiment are thus dispensed with and the space required for them may be saved, making it possible to decrease the diameters of the rolls.

It is not contemplated that the invention be limited to the herein-described embodiments, and considerable deviation in construction is possible within the scope of the invention as defined in the appended claims.

I claim:

1. A rolling mill comprising a pair of rolls and separate journal boxes therefor, a box for one roll being mounted on and being supported solely by the corresponding box for the other roll, preloadable bolt means for directly connecting the upper of the boxes with the lower box and constituting the sole means for positioning and supporting the upper box and for securing the upper box in position on the lower box in stressed position and thereby resisting the upward thrusts of the rolls tending to separate the boxes, and additional means operative while the boxes are in stressed condition for adjusting at least one of the rolls relative to its boxes to relatively adjust the rolls in both axial and radial directions.

2. A rolling mill according to claim 1, wherein said additional adjusting means includes means for axially adjusting one of said rolls relative to its boxes, and means for radially adjusting the other said roll relative to its boxes.

3. A rolling mill comprising a pair of rolls and separate journal boxes therefor, the boxes for one roll being mounted on and being supported solely by the respective corresponding boxes for the other roll, means for anchoring the lower of said boxes to render them immovable, bolt means for directly connecting the upper boxes with the respective lower boxes and constituting the sole means for positioning and supporting the upper boxes and for securing the upper boxes in position on the lower boxes in stressed condition, means for preloading said bolt means, and additional means operative while the boxes are in stressed condition for adjusting at least one of the rolls relative to its boxes to relatively adjust the rolls in both axial and radial directions.

4. A rolling mill according to claim 3 including means for axially and radially immobilizing one of said rolls in its boxes, the said additional means for adjusting the other said roll with respect to its journal boxes comprising sleeve assemblies embracing the journals of said roll, each said assembly comprising a sleeve having an outer cylindrical surface and an inner eccentric cylindrical journal-receiving bore, means for immobilizing the sleeve axially on the journal, means for adjusting said sleeve axially within said box to effect axial adjustment of the roll, and means for rotating said sleeve within the box to effect radial adjustment of the roll.

5. A rolling mill according to claim 4 wherein the said means for adjusting said sleeve axially within the box comprises a radial flange on said sleeve, studs fixed in said box, dogs mounted on and adjustable longitudinally of said studs and engaged with said flange, and means for positively locking said dogs in adjusted position on said studs.
